FUEL PUMP AND NOZZLE FOR INTERNAL-COMBUSTION ENGINES

William V. Falcon, Revere, Mass.

Application June 2, 1947, Serial No. 751,832

4 Claims. (Cl. 299—107.2)

1

My present invention relates to an improvement in fuel pumps and fuel injection valves for use with internal combustion engines of the type in which fuel is injected into the combustion chamber. The invention may be employed either with internal combustion engines of the compression ignition type in which the fuel is ignited by the compression alone or of the electric ignition type in which the fuel is ignited by a timed electric spark.

It is a primary object of my invention to provide a simple combination of fuel pump and fuel valve comprising a rugged structural unit for easy installation and replacement.

My invention provides: (1) An easily removable fuel pump built into a valve body; (2) an easily removable pump plunger; (3) an easily adjustable fuel spray valve; (4) simple fuel valve means operated directly by the pump pressure stroke; and a pump valve unit which may be used in connection with the novel cylinder head described in my companion application Serial No. 719,860, filed January 2, 1947, now Patent No. 2,493,481, dated January 3, 1950, in which are described arrangements by which the fuel is injected into hot air taken from the top of the combustion space so that more perfect and rapid combustion results. The combined unit embodying my invention is extremely simple and compact, has few parts and can be easily replaced by another unit of this invention or by a unit constructed according to my application Serial No. 751,831, filed June 2, 1947.

The invention will be fully understood from the following description, taken in conjunction with the accompanying drawings, in which

Fig. 1 is a vertical section of a portion of a cylinder block and cylinder head of an electric ignition type engine and a combined pump and valve unit constructed according to my invention.

Fig. 2 is an enlarged fragmentary section of the valve unit and related parts; and

Fig. 3 is a section on line 3—3 of Fig. 1.

A cylinder block is shown at 10, a cylinder at 12 and a cylinder head at 14. Within the cylinder head is a circular dome-shaped combustion chamber 16 located over a part only of the cylinder 12. Above the combustion chamber 16 is an auxiliary combustion chamber 18 having a restricted passage 20 between it and the chamber 16 which is formed by an insert 22 screwed into the cylinder head 14. An electric spark type ignition plug (not shown) is screwed into an internally threaded insert 24 to ignite a combustible mixture in the chamber 18 which has

been introduced by the mechanism of the invention. An inner portion 26a of a valve body 26 is secured in a cylindrical aperture 28 through the cylinder head 14, an inner portion 28a of which is reduced forming an internal shoulder 29. A spray valve seat member 30 has a seat 30a which acts as a spray jet and is received with a tight fit into an internal cylindrical bore 32 in the valve body 26 and has a radial flange 34 lying between the end of the valve body 26 and the shoulder 29 in the aperture 28 in the cylinder head. The spray valve seat member 30 abuts against a gasket 36 between it and the end of the aperture 28 and the valve body 26 abuts against a gasket 38 between its end and the flanged shoulder 34 of the spray valve seat member 30, thus making a tight fit between the two units and the cylinder head 14. The gasket 36 prevents escape of the combustion gases in the combustion chamber 16 and the gasket 38 prevents the escape of fuel in the cylindrical bore 32. A fuel nozzle 40 is screwed into the cylinder head 14 at a spaced distance from the spray valve seat 30 thus forming an annular space 42 between them, and it projects slightly into the combustion chamber 16. A passage 44 leads from the auxiliary combustion chamber 18 into another passage 46 which in turn leads to the annular space 42 and thence through a conically shaped passage 48 in the nozzle 40.

A spray valve member 50 has a stem 50a and a head 52 which is seated with a grind fit in the spray valve seat 30a on the combustion chamber end of the valve assembly and it slides in an axial fuel passage 54 in the spray valve seat member 30. Flats 56 are ground on opposite sides of the valve stem 50a to allow free passage of fuel from the left or bottom side of the spray valve seat member 30 to its right or combustion side when the valve 50 is open. The valve 52 is normally held closed or to the left as shown by a compression spring 58 between one end of the seat member 30 and a flanged collar 60 which is adjustably screwed onto a threaded portion 62 of the spray valve stem 50a. The flanged collar 60 is locked in position by a lock nut 64 screwed against it on the stem 50a. A thimble check valve 66 slidably fitted in the cylindrical bore 32 is urged to the left as shown, against a seat 68 by a spring 70 which works against the flanged collar 60. The check valve thimble 66 has a number of drill holes 72 to allow passage of fuel through it when it is raised from its seat 68.

Fuel is supplied by a pump unit designated 74 and its mechanism comprises pump barrel 76

which is grind fitted and rigidly received into a conically shaped aperture 78 in an outer extension 26b of the valve body 26 and oil grooves 80 are provided between them. The pump barrel 76 has a cylindrical bore 82 which leads through a passage 84 through the valve seat 68 forming a fluid connection from the pump into the internal cylindrical bore 32 in the valve body 26. In the cylindrical bore 82 a pump plunger 86 is slidably mounted with oil grooves 88 to prevent leakage of fuel oil past it and it is biased downwardly by a spring 90 urging against the collar of a sleeve 92 which is slidably mounted on the outside of the pump barrel and in turn presses against a plunger head 94 attached to the bottom of the plunger 86. The extension of the valve body 26 which contains the pump barrel 76 has an internally threaded hole 96 into which the fuel oil supply line may be screwed and it leads by a port 98 into the pump cylinder 82 above the plunger 86 when the latter is in its downward position. A check valve member 100 having oil grooves 102 is slidably mounted in an expanded portion of the top of the pump cylinder 82 and it is biased downwardly by a spring 104 against a seat 106 in the pump cylinder 82. The spring 104 works against a plug 108 screwed into the top of the pump barrel 76 which may be removed for priming the pump by allowing the oil to flow through the supply line and into the pump above the plunger which gets rid of any air above the plunger.

The pump plunger 86 is actuated upwardly for a power stroke by a tappet 110 having an adjustable head 112. The tappet is in turn actuated upwardly by cam means not shown, which is adjustable to vary the length and timing of the stroke of the pump plunger 86 in a manner well known in the art which is not a part of this invention. In the cylinder head 14 is provided a priming hole 114 having a seat 116 in its bottom leading into the cylindrical bore 32 of the valve body. A screw threaded stud 118 is mounted with its bottom end tightly in the seat and the stud 118 may be loosened to free the valve system of air and flood it with oil by turning over the engine to operate the pump and then replaced in its seat.

The operation of the mechanism described herein when the engine is running is as follows: The fuel injection system is full of fuel between the pump plunger 86 and the head 52 of the spray valve 50. While the tappet 110 is moving the pump plunger 86 upward the fuel oil above the plunger 86 flows back into the oil line through the port 98 until the upper end of the plunger 86 covers the port 98. Thereafter as the plunger 86 continues to move upwardly the pressure of the fuel oil will rise rapidly in the pump cylinder 82 to lift the check valve 100 and allow the fuel to flow into the passage 84 against the thimble check valve 66 to raise it from its seat 68, through the drill holes 72 into the central portion of the cylindrical bore 32 and along the flats 56 and against the spray valve 50. The fuel oil pumped by any given stroke of the pump plunger 86 does not actually flow all the way through the valve system on each given stroke because the volume of oil contained within the cylindrical bore 32 is large compared to the volume of oil moved on each individual stroke, but there is a generation of pressure which is immediately felt by the fuel oil just under and confined by the head of the valve 50. The fluid pressure generated by the pump raises the valve

50 from the spray valve seat 30 against the pressure of the spring 58 which tends to hold it closed. The valve 50 raises very slightly upon each stroke of the pump plunger 86 and the fuel oil passes between it and the spray valve seat 30 in a circular spray into the annular space 42 where it strikes hot air which has come from the combustion chambers 16 and 18 through the passages 44 and 46. The fuel and hot air are mixed and projected through the spray nozzle 40 at high velocity into the combustion chamber 16 where it is ignited either by an electric spark plug screwed into the cylinder head 14 of the illustration, or by the heat of compression in a compression ignition type engine. As was mentioned there is at all times during operation a volume of oil in the cylindrical bore 32 and this becomes pre-heated before passing through the spray valve 50 and spray valve seat 30 which act as a spray jet. The fuel is further heated upon mixture with hot air in the annular space 42 and since the air and fuel are hot and travelling at high velocity the fuel is broken up into tiny droplets or particles which expand and vaporize by reason of the heat so that an excellent, rapidly combustible mixture of fuel and air is produced. When the upward stroke of the plunger 86 is complete and this occurs considerably before ignition in the combustion chamber 16, the powerful spring 58 rapidly closes the spray valve 50 to prevent back pressure from the combustion chamber and that pressure itself aids the closing of the valve. The volume of oil in the bore 32 is immediately confined from running back into the line by the check valves 66 and 100 so that the pump cylinder 82 is re-filled on the downward stroke of the plunger 86 by new oil from the supply line through the port 98 rather than by back flow from the valve assembly in the bore 32. The spring 58 is much heavier than the check valve spring 70 and the area of the valve 50 is smaller than that of the check valve thimble 66 so that the spray valve 50 will tend to close first and also so that the spring 70 may work against the larger spring for simplicity in assembling. The engine is accelerated by varying the timing and length of stroke of the pump plunger 86 through the variable cam means actuating it.

50 By providing a circular fuel spray around the valve 50 through the fuel spray seat 30 small pinhole type injection jets which can become easily fouled are avoided. The mechanism of the invention is particularly well adapted to high speeds in internal combustion engines and has the great advantage of simplicity.

I claim:

1. In an internal combustion engine of the fuel injection type, said engine including a cylinder head having a cylindrical aperture extending through its wall, an inner portion of said aperture being reduced forming a shoulder, and fuel injection pump plunger mechanism connected to supply fuel under pressure to said aperture, and in combination; fuel valve mechanism for delivering fuel in the form of a spray from said pump mechanism to said cylinder, said valve mechanism comprising a valve body having an inner portion in said aperture and an outer extension rigidly supporting said pump mechanism, the inner portion of said valve body having an enlarged internal bore connected at its outer end to said pump mechanism and open at its inner end, a spray valve seat member received in the open inner end of said bore and

having a radial flange disposed in said aperture in fluid tight abutting engagement between said shoulder and the inner end of said valve body, said valve seat member having an axial fluid passage connecting said internal bore with the interior of said cylinder head, a spray valve member having a head normally closed against said valve seat and opening inwardly of said cylinder head and a stem slidale in said fuel passage with a loose fit to allow flow of fuel through said passage, a collar on said stem and a compression spring in said bore between said collar and said valve seat member holding said valve member normally closed, said spray valve member being forced open and forming a fuel spray jet in cooperation with the said valve seat when the fluid pressure generated by said pump overcomes the force exerted by said compression spring.

2. In an internal combustion engine, the combination as set forth in claim 1 including a check valve in the fluid connection between said pump mechanism and said internal bore.

3. In an internal combustion engine, the combination as set forth in claim 1 including a thimble type check valve in said fluid connection, said check valve being disposed in said internal bore and held normally closed by a compression spring, said spring being located between said check valve and the collar on said valve stem.

4. In an internal combustion engine, the combination as set forth in claim 1 in which said pump plunger and barrel mechanism is received

in a conically shaped aperture in the outer extension of said valve body on an axis at right angles to the axis of said internal bore.

WILLIAM V. FALCON.
